FINGER PROTECTOR FOR TRIGGER HANDS

Walter Ugazio and Edward C. Beccafogli,
Clifton, N. J.

Application December 11, 1946, Serial No. 715,376

2 Claims. (Cl. 42—1)

1

This invention relates to a cold excluding sleeve or cover for protecting the trigger hand of a person using a shot gun or any other shooting device, so that the fingers will not be directly exposed to extreme low temperature conditions and frozen or numbed against free and natural use.

One of the objects of the invention is the provision of a sleeve adapted to receive the hand, wrist and forearm of the shooter, with means for clamping the sleeve in fixed position on the gun, so that the hand may be inserted and removed without difficulty, and cold air may be effectively excluded from the interior of the sleeve.

With the above and other objects in view, the invention comprises certain new and useful constructions, combinations and arrangements of parts, clearly described in the following specification, and fully illustrated in the drawings, in which:

Fig. 1 is a perspective view showing the protective sleeve before being attached to a gun.

Fig. 2 is a perspective view showing the sleeve attached to a gun, and illustrating the arm of a shooter extended through the sleeve into gun firing position.

Fig. 3 is a transverse sectional view, taken on line 3—3 of Fig. 1, looking in the direction of the arrows.

Fig. 4 is a longitudinal sectional view, taken on line 4—4 of Fig. 1, looking in the direction of the arrows.

Referring to the drawings, which illustrate the practical embodiment of the invention, 5 designates the body of the sleeve, shown to be constructed with a longitudinal seam closed by a slide fastener device 6.

The sleeve body 5 when secured about the gun is formed approximately conical, to provide a reduced forward end 7, and a longitudinal slot 8 to allow the breech mechanism of the gun G to project through the protective sleeve.

The forward end of the sleeve is secured in place by means of a U-shaped metal clamp 9, which is secured between the plies of the fabric of which the sleeve is constructed, so that the metal clamp is wholly concealed within the fabric. The U-shaped clamp 9 is thus faced on both sides with fabric, and is shaped to provide opposing approximately parallel jaws 10.

The jaws 10 are clamped against the sides of the gun by means of the screw 11, which is extended through these jaws, and which is engaged by the wing nut 12. The screw is en-

closed for the major portion of its length by a rubber tube 13, which serves to prevent scratching or marring the under-part of the gun in any way.

- 5 The sleeve is constructed with a sufficiently large capacity to freely receive the hand and forearm of an average man, and conforms to the bulk of the coat and hand of the user, so that cold air is effectively excluded from the interior of 10 the protective sleeve, and heat radiated by the person's hand will be confined within the sleeve, and the trigger finger and associated parts of the hand will be protected against freezing or numbing.
- 15 It is understood that various changes in the details of construction, their combination and arrangement, may be made in carrying out the invention, as defined by the claims herein set forth.
- 20 Having described the invention, we claim as new:
1. A finger protector for trigger hands on a gun having a trigger and breech mechanism, comprising a sleeve cover having ends and adapted to be formed into conical shape about the gun, slide fastener means securing the ends of the cover together and releasable to permit the disposing of the sleeve upon the gun, a U-shaped metal clamp open at the top and embedded in the cover material at the forward end of the sleeve cover, said cover when the ends are joined providing for a longitudinally extending slot at the forward end of the cover and extending from the free end of the U-shaped clamp and adapted to allow the breech mechanism of the gun to project therethrough and to allow the clamp to be located ahead of the gun trigger and screw means extending through the free ends of the clamp to bring the same into clamping engagement with the sides of the breech mechanism, said cover depending downwardly from the gun sufficiently to permit the extension of the arm and hand of the user of the gun so that the finger can be located about the trigger and whereby the same 45 will be protected against the cold.

2. A finger protector for trigger hands for a gun having a breech mechanism and a trigger, comprising a sleeve cover of conical shape, a U-shaped metal member embedded in the small 50 end of the cover and having free ends, said cover having a longitudinally extending slot extending rearwardly from the free ends of the U-shaped member and adapted to receive the breech mechanism of the gun, and clamping screw means extending through the U-shaped member and

adapted to bring the free ends of the U-shaped member and the forward end of the sleeve into tight clamping engagement with the breech mechanism, said conical sleeve being of sufficient size as to permit the extension of the hand, forearm, and trigger finger thereinto for the engagement of the trigger finger with the trigger of the gun, the U-clamp being fastened to the gun ahead of the trigger thereof.

WALTER UGAZIO.
